UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER OR LOOSE-SHEET HOLDER.

1,093,369.

Specification of Letters Patent. Patented Apr. 14, 1914.

Application filed September 22, 1913. Serial No. 791,180.

To all whom it may concern:

Be it known that I, GEORGE P. WIGGINTON, a citizen of the United States, residing at Kalamazoo, Michigan, have invented certain new and useful Improvements in Temporary Binders or Loose-Sheet Holders, of which the following is a specification.

This invention relates to improvements in temporary binders or loose sheet holders.

10 My improvements relate particularly to the adjusting mechanism.

I have especially designed my improvements for use in temporary binders or loose sheet holders of the type in which binding 15 strips extend between the covers, such as is shown in United States Letters Patent to Bushong, No. 851,276, issued April 23, 1907. My improvements may however, be readily adapted to binders considerably modified.

20 The main objects of this invention are: First, to provide in a temporary binder or or loose sheet holder an improved adjusting mechanism. Second, to provide in a temporary binder or loose sheet holder an improved 25 adjusting mechanism which may be adjusted either from the inner or the outer sides of the cover containing the adjusting mechanism. Third, to provide an improved temporary binder or loose sheet holder 30 which is simple and economical in structure and very simple in adjustment.

Further objects, and objects relating to structural details will definitely appear from the detailed description to follow.

35 I accomplish the objects of my invention by the devices and means described in the following specification.

The invention is clearly defined and pointed out in the claims.

40 A structure which is a preferred embodiment of my invention is clearly illustrated in the accompanying drawing forming a part of this specification, in which:

Figure I is a detail outside view of a 45 structure embodying the features of my invention, with the covers extended, the outer walls of the covers and also the flexible back strip or back piece being omitted.

Fig. II is a detail central section of a 50 complete binder on a line corresponding to line 2-2 of Fig. I, with the covers closed, sheets being shown in conventional form in the binder. Fig. III is an enlarged detail section on a line corresponding to line 3-3 55 of Fig. I, showing details of the adjusting

mechanism. Fig. IV is an enlarged detail section on a line corresponding to line 4-4 of Fig. I, showing further details of the adjusting mechanism. Fig. V is a detail outside view of a modified structure embodying the features of my invention, the outer walls of the covers and also the flexible back piece being omitted. Fig. VI is a detail section through the binding mechanism on a line corresponding to line 6-6 60 of Fig. V. Fig. VII is a detail section on a line corresponding to line 7-7 of Fig. V. Fig. VIII is a detail section on a line corresponding to line 8-8 of Fig. V.

In the drawing similar reference characters refer to similar parts throughout the several views, and the sectional views are taken looking in the direction of the little arrows at the ends of the section lines.

Referring to the drawing, the covers are 70 designated generally by the numerals 1 and 2. These covers preferably consist of rectangular frames 3, having inner walls 4 and outer walls 5 secured thereto providing chambers within the covers. The frames 80 are preferably of wood, and the inner and outer walls of sheet metal. The outer walls are faced with suitable binding 6, while the inner walls are usually faced with paper or other suitable covering as 7.

85 The structure as illustrated is provided with clamping or binding bars 8 pivotally mounted on the hinge members 9 projecting from the ends of the covers. These clamping or binding bars however, form no part 90 of my present invention, and are therefore not described in detail herein.

The binding strips 10 extend between the covers and are connected to the cover 2 at 11, the other ends of the binding strips are connected to the adjustable member or cross bar 12 at 13. The cross bar 12 is arranged within the chamber of the cover 1 to move longitudinally therein. When the cross bar is drawn toward the outer end of the cover the 100 binding strips are retracted, and when it is moved in the opposite direction they are extended. The adjustable member 12 is provided with an outwardly projecting arm 14, having its end offset to provide a slot engaging part 15, which slides in the longitudinal slot 16 in the inner wall of the cover 1, thus serving as a guide for the cross bar 12.

The adjusting lever 17 is provided with a pivot 18, the pivot being shouldered at 19 110

and having journal portions 20 engaging suitable bearing openings 21 in the inner and outer walls of the cover. See Fig. IV. The swinging end of the lever is arranged 5 under the arm 14 and supports the same with its part 15 in engagement with the slot 16. The lever 17 is provided with a longitudinal slot 22 which engages a roller 23 on the arm 14 so that as the lever is swung the cross 10 bar 12 is moved back and forth to effect the adjustment of the binding strips. The lever 17 is provided with a segment 24 with which the worm 25 coacts. The worm 25 is provided with a journal 26 at one end and with 15 a beveled gear 27 at the other end, the beveled gear being preferably formed on the end of the worm. The worm is provided with an annular bearing groove 25' on the inner side of the gear 27. A bearing bracket 20 28 is provided for the journal end of the worm, while the other end is supported by the bearing bracket 29 having bearing fork 29' engaging the bearing groove 25'. The beveled actuating gear 30 is arranged with 25 its axis at right angles to the plane of the cover, one end being journaled in the bracket 29, and the other in the outer wall of the cover. The actuating gear thus serves to maintain the worm in the bearing 29'. The 30 journal of the actuating gear has a key opening 31 adapted to receive a key 32 at either end, and the walls of the cover have registering openings so that the mechanism may be manipulated from either the outside or the 35 inside of the cover. The mechanism is thus all contained within the cover and is self-locking, that is, the worm and segment serve to hold the parts in their adjusted position without other locking means.

40 In the modifications shown in Figs. V to VIII inclusive, the adjusting lever 33 is connected to the adjustable member 12 by means of the link 34. The adjustable member 12 in this structure is guided by the roller 34 45 which travels between the guides 35 on the inner wall of the cover. The pivot 36, by which the link 34 is connected to the cross member 12, constitutes the journal for the roller. The lever 33 is provided with a 50 ratchet 37 with which the pawl 38 coacts, the pawl being pivoted at 39 on the inner wall of the cover, and held yieldingly in engagement with the ratchet by the spring 40 or held out of engagement by the spring, the spring being 55 adapted to swing past the center of the pivot as the pawl is rocked to and from engaging position, so that the spring performs the double purpose or function of holding the pawl in engagement with the ratchet, 60 and of holding it in its inoperative or disengaged position. The end of the pawl is turned laterally to provide a finger piece 41 which projects through a slot 42 in the inner wall of the cover. The pivot 43 of the lever 65 33 is provided with a key opening 45 adapt-

ed to receive a key at both ends so that the lever may be adjusted from the inner or outer sides of the cover. In this construction the binding strips are released by disengaging the pawl, thus affording a rapid 70 opening device, that is, one in which the mechanism is released by the disengagement of the pawl so that the binding strips may be fully extended. The binding strips may also be quickly retracted. This structure is 75 more rapid in its adjustment than that shown in Fig. I, but requires somewhat more power to operate the same and does not have the self or automatic locking features of the structure shown in Fig. I. The back strip 80 or member 46 telescopes into the cover chambers and is connected to one of the covers as by the spring 47, and is preferably connected to the adjustable member 12 carried by the other cover, the connections to the adjustable member 12 not being shown as they form no part of this invention. Suitable 85 connections are shown in Patent No. 851,276, dated April 23, 1907, to H. F. Bushong.

My improved temporary binder or loose 90 sheet holder is simple and economical in its parts, and they are easily assembled. It is also very easily and quickly manipulated.

Having thus described my invention, what I claim as new and desire to secure by Letters Patent is:

1. The combination with the covers, one of said covers comprising a frame with outer and inner walls providing a chamber therein, the inner wall being longitudinally slotted, binding strips extending between said covers, a cross bar to which said binding strips are connected, arranged in said chamber, the other ends of said binding strips being connected to the other cover, said cross bar being provided with an outwardly projecting arm having a part engaging said slot in the inner wall of said cover, a lever provided with a segment, pivoted in the front and rear walls of said cover, said lever being arranged under said arm on said cross bar to support the same in engagement with said slot in said wall and being longitudinally slotted to engage a roller in said arm, a worm coacting with said segment, said worm being provided with a journal at one end and a beveled gear at the other, there being an annular bearing groove at the inner side of said gear, a bearing bracket for the journal on said worm, a bearing bracket having a forked bearing engaging said bearing groove of said worm, said bearing brackets being disposed on the inner wall of said cover, and a beveled actuating gear coacting with said gear on said worm and journaled in said bearing bracket for the gear end of said worm and in the inner cover, said actuating gear being arranged on the inner side of said gear on said worm, whereby said worm is retained in said 105 110 115 120 125 130

forked bearing, the journal of said actuating gear being adapted to receive a key at both ends.

2. The combination with the covers, one of said covers comprising a frame with outer and inner walls providing a chamber therein, the inner wall being longitudinally slotted, binding strips extending between said covers, a cross bar to which said binding strips are connected, arranged in said chamber, the other ends of said binding strips being connected to the other cover, said cross bar being provided with an outwardly projecting arm having a part engaging said slot in the inner wall of said cover, a lever provided with a segment, pivoted in the front and rear walls of said cover, said lever being arranged under said arm on said cross bar to support the same in engagement with said slot in said wall and being longitudinally slotted to engage a roller on said arm, a worm coacting with said segment, said worm being provided with a journal at one end and a beveled gear at the other, there being an annular bearing groove at the inner side of said gear, a bearing bracket for the journal on said worm, a bearing bracket having a forked bearing engaging said bearing groove of said worm, said bearing brackets being disposed on the inner wall of said cover, and a beveled gear coacting with said gear on said worm and journaled in said bearing bracket for the gear end of said worm and in the inner cover, said actuating gear being arranged on the inner side of said gear on said worm, whereby said worm is retained in said forked bearing.

3. The combination with the covers, one of said covers comprising a frame with outer and inner walls providing a chamber therein, binding strips extending between said covers, a cross bar to which said binding strips are connected, arranged in said chamber, the other ends of said binding strips being connected to the other cover, a guide for said cross bar, a lever provided with a segment, pivoted in the front and rear walls of said cover, and operatively connected to said cross bar, a worm coacting with said segment, said worm being provided with a journal at one end and a beveled gear at the other, there being an annular bearing groove at the inner side of said gear, a bearing bracket for the journal on said worm, a bearing bracket having a forked bearing engaging said bearing groove of said worm, said bearing brackets being disposed on the inner wall of said cover, and a beveled actuating gear coacting with said gear on said worm and journaled in said bearing bracket for the gear end of said worm and in the inner cover, said actuating gear being arranged on the inner side of said gear on said worm, whereby said worm is retained in said forked bearing.

by said worm is retained in said forked bearing, the journal of said actuating gear being adapted to receive a key at both ends.

4. The combination with the covers, one of said covers comprising a frame with outer and inner walls providing a chamber therein, binding strips extending between said covers, a cross bar to which said binding strips are connected, arranged in said chamber, the other ends of said binding strips being connected to the other cover, a guide for said cross bar, a lever provided with a segment, pivoted in the front and rear walls of said cover, and operatively connected to said cross bar, a worm coacting with said segment, said worm being provided with a journal at one end and a beveled gear at the other, there being an annular bearing groove at the inner side of said gear, a bearing bracket for the journal on said worm, a bearing bracket having a forked bearing engaging said bearing groove of said worm, said bearing brackets being disposed on the inner wall of said cover, and a beveled actuating gear coacting with said gear on said worm and journaled in said bearing bracket for the gear end of said worm and in the inner cover, said actuating gear being arranged on the inner side of said gear on said worm, whereby said worm is retained in said forked bearing.

5. The combination with the covers, one of said covers comprising a frame with outer and inner walls providing a chamber therein, the inner wall being longitudinally slotted, binding strips extending between said covers, a cross bar to which said binding strips are connected, arranged in said chamber, the other ends of said binding strips being connected to the other cover, said cross bar being provided with an outwardly projecting arm having a part engaging said slot in the inner wall of said cover, a lever provided with a segment pivoted on the front and rear walls of said cover, said lever being arranged under said arm on said cross bar to support the same in engagement with said slot in said wall and being longitudinally slotted to engage a roller on said arm, a worm coacting with said segment, a beveled gear on said worm, and a beveled actuating gear coacting with said gear on said worm, journaled in bearings on said front and rear cover walls, the journal of said actuating gear being adapted to receive a key at both ends.

6. The combination with the covers, one of said covers comprising a frame with outer and inner walls providing a chamber therein, the inner wall being longitudinally slotted, binding strips extending between said covers, a cross bar to which said binding strips are connected, arranged in said chamber, the other ends of said binding strips being connected to the other cover, said cross

bar being provided with an outwardly projecting arm having a part engaging said slot in the inner wall of said cover, a lever provided with a segment pivoted on the 5 front and rear walls of said cover, said lever being arranged under said arm on said cross bar to support the same in engagement with said slot in said wall and being longitudinally slotted to engage a roller on said arm, 10 a worm coacting with said segment, a beveled gear on said worm, and a beveled actuating gear coacting with said gear on said worm, journaled in bearings on said front and rear cover walls.

15 7. The combination with the covers, one of said covers comprising a frame with outer and inner walls providing a chamber therein, binding strips extending between said covers, a cross bar to which said binding strips are connected, arranged in said chamber, the other ends of said binding strips being connected to the other cover, a lever provided with a segment, pivoted on the front and rear walls of said cover, and operatively 20 connected to said cross bar, a worm coacting with said segment, a beveled gear on said worm, and a beveled actuating gear coacting with said gear on said worm, journaled in bearings on said front and rear cover walls,

25 30 the journal of said actuating gear being adapted to receive a key at both ends.

8. The combination with the covers, one of said covers comprising a frame with outer and inner walls providing a chamber therein, binding strips extending between said covers, a cross bar to which said binding strips are connected, arranged in said chamber, the other ends of said binding strips being connected to the other cover, a lever 35 provided with a segment, pivoted on the front and rear walls of said cover, and operatively connected to said cross bar, a worm coacting with said segment, a beveled gear on said worm, and a beveled actuating gear 40 coacting with said gear on said worm, journaled in bearings on said front and rear cover walls.

45 9. The combination with the covers, one of the covers having a chamber therein, binding strips extending between said covers, an adjustable member to which said binding strips are connected arranged in 50 in said chamber in said cover, a pivoted lever provided with a segment, said lever having operative connection with said adjustable member, a worm coacting with said segment, said worm being provided with a journal at one end, and a beveled gear at the other, there being an annular 55 bearing groove at the inner side of said gear, a bearing for said journal on said worm, a forked bearing engaging said bearing groove of said worm, and a beveled actuating gear coacting with said gear on said worm, said 60 actuating gear being arranged on the inner

side of said gear on said worm, whereby said worm is retained in said forked bearing.

10. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, 70 said lever being operatively connected to said adjustable member, a worm coacting with said segment, a beveled gear on said worm, and a beveled actuating gear coacting with said gear on said worm, the axis of said actuating gear being disposed at right angles to the plane of the cover, the journal of said actuating gear being adapted to receive a key at both ends.

11. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, 80 said lever being operatively connected to said adjustable member, a worm coacting with said segment, a beveled gear on said worm, and a beveled actuating gear coacting with said gear on said worm, the axis of said actuating gear being disposed at right angles to the plane of the cover, the journal of said actuating gear being adapted to receive a key at both ends.

12. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, 90 said lever being operatively connected to said adjustable member, a worm coacting with said segment, a beveled gear on said worm, and a beveled actuating gear coacting with said gear on said worm, the axis of said actuating gear being disposed at right angles to the plane of the cover.

13. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, 100 said lever being operatively connected to said adjustable member, a worm coacting with said segment, a beveled gear on said worm, and a beveled actuating gear coacting with said gear on said worm, the axis of said actuating gear being disposed at right angles to the plane of the outer wall of the cover, and adapted to be operated 105 from the inner and outer side of the cover.

14. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, 110 said lever being operatively connected to said adjustable member, a worm coacting with said segment, a beveled gear on said worm, and a beveled actuating gear coacting with said gear on said worm, the axis of said actuating gear being disposed at right angles to the plane of the outer wall of the cover, and adapted to be operated 115 from the inner and outer side of the cover.

15. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, 120 said lever being operatively connected to said adjustable member, a worm coacting with said segment, a beveled gear on said worm, and a beveled actuating gear coacting with said gear on said worm, the axis of said actuating gear being disposed at right angles to the plane of the outer wall of the cover, and adapted to be operated 125 from the inner and outer side of the cover.

the plane of the outer wall of the cover, and adapted to be operated from the outer side of the cover.

14. The combination with the covers, one of said covers having a chamber therein, binding strips extending between said covers, an adjustable member to which said binding strips are connected, arranged in said chamber, the other ends of said binding strips being connected to the other cover, a pivoted lever provided with a segment, said lever being operatively connected to said adjustable member, a worm coacting with said segment, a beveled gear on said worm, and a beveled actuating gear coacting with said gear on said worm, the axis of said actuating gear being disposed at right angles to the plane of the cover.

15. The combination with the covers, one of said covers having a chamber therein, binding strips extending between said covers, an adjustable member to which said binding strips are connected, arranged in said cover chamber, the other ends of said binding strips being connected to the other cover, a guide for said adjustable member, a pivoted lever operatively connected to said adjustable member, said lever being adapted to be adjusted from the inner and the outer sides of the cover.

16. The combination with the covers, one of said covers comprising a frame and inner and outer walls secured thereto, providing a chamber therein, binding strips extending between the said covers, an adjustable member to which said binding strips are connected, arranged in said chamber, the other ends of said binding strips being connected to the other cover, and a lever journaled on the front and rear walls of said cover, said lever being operatively connected to said adjustable member, said lever being adapted to be manipulated from either the inner or outer sides of said cover by means of a key.

17. The combination with the covers, one of said covers having a chamber therein, binding strips extending between said covers, an adjustable member to which said binding strips are connected, arranged in said cover chamber, the other ends of said binding strips being connected to the other cover, and a pivoted lever operatively connected to said adjustable member, said lever being adapted to be adjusted from the inner and the outer sides of the cover by means of a key.

18. The combination with the covers, one of said covers having a chamber therein, binding strips extending between said covers, an adjustable member to which said binding strips are connected arranged with in said chamber, the other ends of said bind-

ing strips being connected to the other cover, a segment operatively connected to said adjustable member, a worm coacting with said segment, a beveled gear on said worm, and a beveled actuating gear coacting with said gear on said worm, the axis of said actuating gear being disposed at right angles to the plane of the cover.

19. The combination with the covers, binding strips extending between said covers, an adjustable member to which said binding strips are connected, carried by one of the covers, the other ends of said binding strips being connected to the other cover, a pivoted lever provided with a segment, said lever being operatively connected to said adjustable member, a worm coacting with said segment, a beveled gear on said worm, and a beveled actuating gear coacting with said gear on said worm, the axis of said actuating gear being disposed at right angles to the plane of the cover and being adapted to be operated from the inner and outer sides of the cover.

20. The combination with the covers, binding strips extending between said covers, an adjustable member to which said binding strips are connected, carried by one of the covers, the other ends of said binding strips being connected to the other cover, a pivoted lever provided with a segment, said lever being operatively connected to said adjustable member, a worm coacting with said segment, a beveled gear on said worm, and a beveled actuating gear coacting with said gear on said worm, the axis of said actuating gear being disposed at right angles to the plane of the outer wall of the cover and being adapted to be operated from the side of the cover.

21. The combination with the covers, one of said covers having a chamber therein, binding strips extending between said covers, an adjustable member to which said binding strips are connected arranged within said chamber, the other ends of said binding strips being connected to the other cover, means for adjusting said adjustable member comprising a worm, a beveled gear on said worm, and a beveled actuating gear coacting with said gear on said worm, the axis of said actuating gear being disposed at right angles to the plane of the cover and adapted to be operated from the side of the cover.

22. The combination with the covers, one of said covers having a chamber therein, binding strips extending between the covers, an adjustable member to which said binding strips are connected arranged in said chamber, the other ends of said binding strips being connected to the other cover, a pivoted lever provided with a segment, said lever being operatively connected to said adjustable member, a worm coacting with

- said segment, and means for actuating said worm comprising an actuating gear disposed with its axis at right angles to the plane of the cover.
23. The combination with the covers, one of said covers having a chamber therein, binding strips extending between the covers, an adjustable member to which said binding strips are connected arranged in said chamber, the other ends of said binding strips being connected to the other cover, a pivoted lever operatively connected to said adjustable member, and means for actuating said lever comprising an actuating gear disposed with its axis at right angles to the plane of the cover.
24. The combination with the covers, one of said covers having a chamber therein, binding strips extending between the covers, an adjustable member to which said binding strips are connected arranged in said chamber, the other ends of said binding strips being connected to the other cover, means for adjusting said adjustable member comprising a worm, and means for actuating said worm comprising an actuating gear disposed with its axis at right angles to the plane of the cover and adapted to be operated from the side of the cover by means of a key.
25. The combination with the covers, one of said covers having a chamber therein, binding strips extending between the covers, an adjustable member to which said binding strips are connected arranged in said chamber, the other ends of said binding strips being connected to the other cover, and means for adjusting said adjustable member comprising an actuating gear disposed with its axis at right angles to the plane of the cover and adapted to be operated from the side of the cover by means of a key.
26. The combination with the covers, one of said covers having a chamber therein, binding strips extending between the covers, an adjustable member to which said binding strips are connected arranged in said chambered cover for adjustment longitudinally of the cover, the other ends of the binding strips being connected to the other cover, means for adjusting said adjustable member and retaining it in its adjusted positions within said chamber comprising a screw, and an actuating gear therefor disposed with its axis at right angles to the plane of the cover and adapted to be operated from the inner and outer sides of the cover by means of a key.
27. The combination with the covers, one of said covers having a chamber therein, binding strips extending between the covers, an adjustable member to which said binding strips are connected arranged in said chambered cover for adjustment longitudinally of the cover, the other ends of the binding strips being connected to the other cover, means for adjusting said adjustable member and retaining it in its adjusted positions within said chamber comprising a screw, and an actuating gear therefor disposed with its axis at right angles to the plane of the cover and adapted to be operated from the side of the cover.
28. In a temporary binder, the combination with the covers, of a binder adjusting means comprising an adjustable member connected to one of the covers, means for adjusting said adjustable member carried by the other cover and comprising a pivoted lever connected to said adjustable member, an actuating screw for said lever, and driving gears for said screw, one of said gears being disposed with its axis at right angles to the plane of the cover and adapted to be operated from the side of the cover.
29. In a temporary binder, the combination with the covers, of binder adjusting means comprising an adjustable member connected to one of the covers, means for adjusting and retaining said adjustable member in its adjusted positions carried by the other cover and comprising a screw, and an actuating gear for said screw disposed with its axis at right angles to the plane of the cover and adapted to be operated from the side of the cover.
- In witness whereof, I have hereunto set my hand in the presence of two witnesses.
